ABSTRACT: A device for replicating ice crystals or water droplets which comprises a housing enclosing a cavity in which is mounted an electrical heating element suitably connected to a power source. The resistance wire on the element is coated with the monomer, methyl 2-cyanoacrylate, which when heated vaporizes filling the cavity. Ice crystals or water droplets falling through the vapor are coated with the monomer as they drop to the bottom of the container. The coated droplets or crystals are dehydrated leaving replicas which can be viewed through a microscope.

APPARATUS FOR REPLICATING ICE CRYSTALS

GOVERNMENT INTEREST

The invention described herein may be manufactured and used by or for the Government of the United States of America for governmental purposes without the payment of any royalties thereon or therefor.

BACKGROUND OF THE INVENTION

This invention relates to a method and apparatus for replicating ice crystals and water droplets.

In the field of weather modification investigation of the growth of water droplets and ice crystals under varying conditions has provided a great deal of information on the ice crystal growth mechanism, the distribution of charges on the crystal surfaces, and atmospheric processes such as crystal clustering, and ice crystal multiplication techniques. Nakaga in "Compendium of Meteorology, American Meteorology Society," Boston, (1954), and Hallet and Mason in the "Proceedings of the Royal Society;" London, Ser. A, 247, 440 (1958) observed the ice crystal habit dependence on temperature; Vonnegut in "G.E. Research Laboratory Project Cirrus," Report No. 5 (1948), Schaefer in "Chemical Revue," page 44 (1949), and others have reported on the effects of vapor contaminants in the atmosphere on the crystal habit. The present device is a simple means for replicating ice crystals and water droplets useful in the field of weather modification.

It is therefore an object of the present invention to provide a simple method and apparatus for preserving in detail the features of ice crystals and water droplets for use in the study of air and water problems.

DESCRIPTION OF THE DRAWING

FIG. 1 in partial section illustrates one embodiment of the present invention;

FIG. 2 is an isometric of another embodiment of the invention;

FIG. 3 section of the face of FIG. 2; and

FIG. 4 is an exploded view of the coated resistance wire used in both embodiments.

BRIEF DESCRIPTION OF THE INVENTION

Referring now to the drawing there is shown in FIG. 1 an embodiment of the present invention which comprises a cylindrical housing 11 having walls about one-half inch thick. The walls enclose a cavity or cloud chamber 17. A metal collar 14 fits into recess 16 which is formed on the top edge of housing 11. Collar 14 may be welded to the housing wall or molded as a part of the housing preform. A heating element comprising a resistance wire 15 coated with methyl 2-cyanoacrylate 26 is mounted on the inner wall of collar 14, and connected by leads 18 to a suitable power source, in this instance, a 1-1 volt battery (not shown). The wire used was the nickel-chromium alloy, Nichrome, but other wire generally used in heating elements such as Chromel, Tophet, copper, etc., is suitable. Cavity 17 is closed by means of a metal disc 19 which moves around steel pin 20 positioned on the top edge of collar 14. A movable circular plate 12 forms the base of housing 11. Plate 12 is easily removed. A groove 13 is provided around the perimeter of plate 12 and is of dimensions such as to closely engage the bottom edge of said housing 11. A bore is provided in the wall of cylinder 11 in which a thermometer 21 is mounted for measuring the temperature of the cylinder. In operation when the power source is actuated heating of the wire causes vaporization of the monomer thereby filling the cavity in about 40-60 seconds. Disc 19 is moved so as to open chamber 17 and ice crystals or water droplets are permitted to fall through the monomer vapor cloud onto plate 12. The monomer coats the crystals or droplets as they fall. In about 30-60 seconds the cavity is closed. Additional

monomer is allowed to deposit on the ice crystals or water droplets for about 30 seconds. The plate on which the coated crystals or droplets are deposited is now carefully removed and stored in a cold desiccator until dehydrated. The film forming the surface of the crystals is thin and fragile so care must be taken to allow a gradual change of pressure if the samples are placed in a vacuum system such as might occur if placed on the viewing stage of an electron microscope. The dehydrated samples should be placed in a closed container. In the presence of water the thin films may deteriorate and do deteriorate rapidly in the presence of certain organic vapors.

There is shown in FIG. 2 another embodiment of this invention which is fairly rugged and is used in the field. It comprises a metal housing 22, having a bore 23 extending through one end. Bore 23 is closed on the backside 24 of housing 22 by means of a heating unit designated 25 which is suitably connected by leads 34 to a power source connected at 33. The unit is provided with resistance wire 15 coated with methyl 2-cyanoacrylate 26 illustrated in FIG. 4. Heating unit 25 extends about midway into bore 23 which is closed on the front face 27 of housing 22 by a shutter 28 illustrated in FIG. 3. Shutter 28 is moved when spring 31 is actuated by a turn of knob 29 which is mounted on shaft 30 positioned on the backside 24 of housing 22. Knob 29 also fits over a microswitch 32 and movement of the knob initiates the power source at 33 and at the same time causes opening of shutter 28. Actuation of the power source at 33 causes wire 15 to heat up sufficiently to vaporize the monomer coating 26. In operation this device is placed face down over a substrate on which water droplets or ice crystals are deposited. The shutter is opened and the vapor which is created by the simultaneous heating of the coated wire forms a film on the droplets which are then slowly dehydrated leaving replicas. A 15 to 20 second exposure is sufficient to coat the ice crystals or droplets with enough monomer that areas with high curvature maintain their shape after evaporation of the water. For replication of larger areas it is necessary to deposit a heavier coating of the monomer.

Replicas made by this invention may be viewed with dark field or phase contrast illumination if glass slides are used as a substrate, or are positioned on the bottom of the replicating device. If the sample is to be examined by a scanning microscope, the replica is prepared on a metal slide or substrate and then coated with a gold or gold-palladium film.

The coated wire or filament for this device was constructed from 0.05 cm. diameter resistance Nichrome wire. The cold resistance of the wire is approximately 0.04 ohms/cm. The grid or framework is formed so a supply of the liquid monomer, methyl 2-cyanoacrylate, is maintained in the sharp bends of the wire as shown in FIG. 4. A single loading of 50 to 100 mg. of the monomer is sufficient for several replications. A 1.5 volt dry cell battery with an external 0.5 ohm resistor is suitable for the power supply. The monomer used herein is relatively stable in the absence of water. The temperature of the replicator should be stabilized before use and it should be stored in a thermally insulated carrier after use.

What we claim is:

1. A device for replicating water droplets and ice crystals comprising:

a housing enclosing a cavity for receiving ice crystals and water droplets, provided with at least one movable closure means;

a resistance wire coated with methyl 2-cyanoacrylate mounted within said cavity; and

a power source positioned outside said cavity to which said coated wire is suitably connected;

whereby actuation of the power source causes heating of the wire thereby generating a cloud of methyl 2-cyanoacrylate which coats said droplets and crystals as they come in contact with the methyl 2-cyanoacrylate.

2. The device in accordance with claim 1 wherein said housing is provided with two movable closure means whereby said crystals and droplets can enter at one side and be removed from the other side.
